DANIEL S. HOLT, OF MITTINEAGUE, MASSACHUSETTS, ASSIGNOR TO STRATHMORE PAPER COMPANY, OF MITTINEAGUE, MASSACHUSETTS, A CORPORATION OF MASSACHUSETTS.

RECORDING-HYDROMETER.

1,341,014.

Specification of Letters Patent. Patented May 25, 1920.

Application filed July 14, 1919. Serial No. 310,762.

To all whom it may concern:

Be it known that I, DANIEL S. HOLT, a citizen of the United States of America, residing at Mittineague, in the county of 5 Hampden and State of Massachusetts, have invented certain new and useful Improvements in Recording-Hydrometers, of which the following is a specification.

This invention relates to improvements 10 in recording hydrometers.

I am aware that recording hydrometers have been provided heretofore and that various types of recording hydrometers will 15 be found in the prior art. Such hydrometers however, are characterized in that the recording pen, or some actuating part thereof, is carried by the hydrometer bulb itself, which necessarily requires special structure 20 of the hydrometer and special calibration thereof, all of which I seek to avoid.

According to one feature of this invention, I provide a recording hydrometer, which makes use of a standard hydrometer bulb, such bulb being normally free to float 25 in the fluid being tested, and which includes a record pen periodically movable to plot the hydrometer reading, the movement of the pen to plotting position being limited by the height of the hydrometer relative to 30 the fluid being tested.

According to another feature of the invention, means are provided to periodically grip the hydrometer bulb and hold it 35 against flotation while a member descends upon it and such member is arranged to move the recording pen.

According to another feature of the invention, the movable member, which descends upon the hydrometer bulb, is connected 40 to the recording pen through the intermediary of a thermometric mechanism, such for example as that employed in standard recording thermometers, and such mechanism is connected to the fluid being tested 45 to move the pen relatively to said member according to temperature variations in the fluid, whereby an automatic correction of the specific gravity readings for temperature variations is obtained.

50 According to another feature of the invention, I employ a standard recording thermometer but mount the active mecha-

nism thereof on a member, which is periodically moved to a new position on the record sheet and is limited in such movement by 55 the height of the hydrometer in the fluid.

According to another feature of the invention, means are provided to cause a shifting of the recording pen, as just described, and means are provided to move the 60 pen into and out of engagement with the record sheet at proper times and in coördinated relation with the shifting of the pen, so that the latter is held away from the sheet while it is being shifted. 65

According to a further feature of the invention, means are provided to automatically flush the hydrometer at periodic intervals.

Other features and advantages will appear in the following description and in the 70 illustrative embodiment of the invention in the accompanying drawings, in which—

Figure 1 is a front exterior elevational view of the complete apparatus; 75

Fig. 2 is a sectional elevational view thereof with the actuating mechanism removed;

Fig. 3 is a fragmentary cross-sectional view, taken on the line 3—3 of Fig. 2, and 80 illustrates the mechanism for moving the pen to and from its record sheet;

Fig. 4 is an enlarged sectional view of a part of Fig. 3;

Fig. 5 is a fragmentary plan view, taken 85 on the line 5—5 of Fig. 2, and illustrates the mechanism for operating the control valve for the hydrometer flushing device;

Fig. 6 is a sectional plan view, taken on the line 6—6 of Fig. 2, and illustrates the 90 sample can for the fluid to be tested;

Fig. 7 is a perspective view illustrative of the hydrometer clamping device;

Fig. 7^a is a perspective view illustrative 95 of a detail shown in Fig. 2;

Fig. 8 is an enlarged front elevational view of the actuating mechanism shown in Fig. 1;

Fig. 9 is a rear elevational view thereof;

Fig. 10 is a fragmentary perspective view 100 of the escapement wheel of the actuating mechanism;

Fig. 11 is a fragmentary elevational view further illustrating the escapement;

Fig. 12 is a fragmentary sectional plan view taken on the line 12—12 of Fig. 11;

Fig. 13 is a fragmentary perspective view illustrative of a detail of the actuating mechanism;

Fig. 14 is an elevational view of the actuating mechanism for the flushing water control valve;

Fig. 15 is an elevational view of the actuating mechanism for the hydrometer clamping device;

Fig. 16 is an enlarged fragmentary sectional view of a part of Fig. 15;

Fig. 17 is an elevational view of the cam 15 for shifting the pen arm to and from the position for recording the hydrometer readings;

Fig. 18 is an elevational view of the mechanism for moving the pen into and out of engagement with the record sheet; and

Fig. 19 is a plan view of a part of Fig. 18;

Fig. 20 is a diagrammatical view illustrative of the electrical connections of the apparatus.

25 The apparatus, in general, comprises, a movable record sheet; a temperature recording mechanism to operate on such sheet; a sample can to receive the fluid whose temperature and specific gravity is to be measured and recorded; a hydrometer; clamping mechanism operable periodically to grip the hydrometer and frictionally hold it in whatever position it may be; mechanism to shift the temperature recording mechanism 30 as a unit to a different position on the record sheet so that the temperature recording pen may likewise plot the specific gravity reading, the shifting of the temperature recording mechanism being limited by means 35 of engageable with the clamped hydrometer for this purpose; mechanism associated with the shifting mechanism to move the recording pen away from the record sheet prior to the shifting movement in one direction 40 and into engagement with the sheet at one end of such movement and to reverse such operations for the shifting movement in the opposite direction; mechanism to flush the hydrometer after each reading has been 45 taken; and actuating mechanism to periodically operate the various mechanisms described and coördinate them one with another.

50 Referring to Fig. 1; A represents the casing of the apparatus, which is of rectangular box-like form and receives within it most of the various unit mechanisms described. The front face of casing A is largely closed in by upper and lower cover plates B and C, respectively, which plates are readily removable to permit access to the interior mechanism.

55 The movable record sheet is of usual form. As shown, it consists of a circular sheet s, 60 suitably held to a disk d, which is revoluble

about the axis a by suitable mechanism, such as clockwork, which may be supported on the rear face of cover plate B. In this instance, the driving means for sheet s is an electric clock, which is controlled electrically from a master clock in a manner well understood in the art. Detailed illustration and description of the driving means for sheet s is thought unnecessary to an understanding of the invention and it will suffice to state that sheet s is so moved that the generally radial ordinates o on sheet s will represent time.

65 The temperature recording mechanism is also of known and usual form. It is indicated generally and conventionally by T, and p is the recording pen, r the arm carrying pen p; t the tube connecting mechanism to the thermometric bulb b which is disposed in a sample can 20 located at the base of casing A. Further description of the temperature recording mechanism is thought unnecessary to an understanding of the invention and for a more complete disclosure reference is made to U. S. Letters Patent No. 659,616, granted October 9, 1900, to William H. Bristol.

70 The sample can 20, (Fig. 2) is merely a cylindrical sleeve closed at its base by a cored member 21, by means of which it is supported from the base of casing A. A passage 22 in member 21 is connected at one end with an inlet pipe 23 and opens at the other end into the base of the sample can 20. A plate 24, preferably with a serrated periphery (Fig. 6), is supported from and in spaced relation with the member 21 and with the sample can, to overlie the inlet passage 22 and prevent the incoming fluid from disturbing the fluid thereabove and the consequent interference with the hydrometer readings. Surrounding the sample can and likewise supported on member 21 is an overflow tank 25, the base of which 75 communicates, by way of a passage 26 in member 21 with an outlet pipe 27. The fluid to be measured is continuously supplied to the bottom of the sample can 20 and overflows from the top thereof into tank 25.

80 The hydrometer, of usual commercial form, is represented conventionally at h in Fig. 2. It normally floats freely in the fluid contained in sample can 20 and is guided against lateral displacement between a finger 29 and upper and lower fingers 28. All 85 the fingers are bent up from wire, the finger 29 being straight and the fingers 28 being bent to afford a recess 30 through which the hydrometer may ordinarily freely move. The fingers 28 are fixed to a block 31 supported by the rear wall of casing A and the finger 29 is integrally formed, or otherwise attached, to an upwardly and vertically extending rod 32, the lower end of which is rotatably mounted in block 31. The upper 90

end of rod 32 is rotatably mounted in a bearing 33 on the rear wall of casing A and carries an arm 34, the free end of which is connected by a horizontal link 35 to a lever 36 5 pivoted at 37 to a bracket on the rear wall of casing A. The outer end of lever 36 is weighted, as at 38, and the connection of link 35 to lever 36 is closely adjacent the fulcrum 37 in order to provide sufficient leverage 10 so that a falling movement of the weighted lever 36 will turn rod 32 and finger 29 to firmly clamp the hydrometer h against fingers 28. The lever 36 is normally held in its upper position by a rod 39, which 15 connects it to a unit of the actuating mechanism to be later described. At the proper time rod 39 is released to allow the lever 36 to descend and cause the clamping of the hydrometer and later is lifted by a suitable 20 cam into the illustrated position.

The entire thermometric mechanism T is carried by a frame 40, which is fixed to a horizontal shaft 41 (Fig. 3) oscillatable in a bracket 42 secured to a horizontal cross 25 bar 43 in the casing A. Fixed to shaft 41 is an arm 44 which is connected near shaft 41 by an upwardly extending rod 45 to a second unit of the actuating mechanism to be described. Such unit normally holds arm 44 30 in its upper position, as illustrated, but periodically releases the arm and allows it to descend by gravity. Adjustably secured to the outer end of arm 44 is a bar 46 which is provided with a plurality of holes 47, in any 35 one of which the upper end of a rod 48 may be connected. The adjustable connection of bar 46 and the holes 47 provide a wide range for varying the effective length of arm 44. The rod 48 depends from bar 46 and passes 40 loosely through a loop 49 on the described rod 32 for guiding purposes. On the lower end of rod 49 is a conical cap-like member 50 and such member is approximately vertically in line with the upper end of hydrometer h 45 so that upon a release of arm 44 some part of the cap 50 will engage the upper end of the hydrometer. The conical nature of the cap provides for self-centering of the cap on the top of the hydrometer. The hydrometer is clamped, as already described, before 50 the cap 50 is permitted to descend, so that the hydrometer acts as a stop to limit the degree of tilting of frame 40 by arresting the descent of cap 50.

55 It will thus be seen that the recording pen p may be shifted on sheet s from the position in which it is effective to plot the temperature curve x to a second position in which it is effective to plot the specific gravity readings y . Since the position in which pen p comes to rest at the end of the shifting movement just described is proportional to the distance that the hydrometer h projects above the surface of the fluid in the sample 60 can 20 (which fluid is obviously kept at 65 constant level), the marks y made on sheet s are proportional to the specific gravity of such fluid and may by suitable calibration be made to read directly in any desired units of specific gravity, such as degrees Baumé 70 for example. Since it seldom happens that any two hydrometers h will be exactly alike, the adjustable connection of rod 48 to arm 44 is provided so that upon the substitution of a new hydrometer, the degree of tilting 75 of pen p may be adjusted until the specific gravity graduations on sheet s correctly indicate the position of hydrometer h in the sample can 20.

The fact that the pen used to plot the 80 hydrometer readings is connected to frame 40 through the intermediary of a thermometric mechanism, whether or not such mechanism is used to plot a temperature curve x , makes possible an automatic correction of the 85 hydrometer readings for variation in temperature of the fluid being tested, so that true specific gravity readings are plotted on the record sheet s . Assume, for example, that 60 degrees Fahrenheit is the temperature 90 at which the indications on the hydrometer correctly indicate the specific gravity of the fluid, then if the temperature exceeds this figure, the pen p will be moved proportionately, and relatively to frame 40, 95 radially outward on the record sheet s so that when the frame 40 is later moved inwardly to plot the hydrometer reading the pen p will not be moved so far as it otherwise would be. Conversely, if the temperature 100 is below the standard temperature, the pen p will be moved by mechanism t radially inwardly, so that on shifting of the frame 40 to its inner position pen p will be moved radially inwardly farther than it 105 would be by the shifting mechanism alone. Thus, the hydrometer readings are automatically corrected for temperature and true 110 corrected readings only are plotted on the record sheet s . The length of the pen arm r is made of such length and the temperature and specific graduations on sheet s are so proportioned that the radial movement of pen p by the thermometric mechanism t correctly indicates on the specific gravity chart 115 the proper correction of the specific gravity readings for temperature.

Since the pen p is periodically shifted from temperature to specific gravity plotting position, it is necessary to move the pen p away from sheet s prior to each shifting movement of frame 40 in each direction and to then move it into engagement with the sheet s after the end of each shifting movement. Referring to Figs. 3 and 4, the pen arm r is long and slender and has one end fixed to the frame of mechanism T. The pen arm r , therefore, has considerable spring and it is such spring, in this instance, which holds pen p against the record sheet s , 125 130

Mounted to slide horizontally in frame 40 are two parallel wires 51, which are connected at their forward ends by a cross bar 52, so positioned as to engage the arm *r* on 5 outward movement and cause pen *p* to be moved out of contact with sheet *s*. The inner ends of wires 51 are likewise connected together by an integral cross bar 53 which abuts a lever 54 pivoted at its upper 10 end to frame 40. A bow spring 55, disposed between the frame 40 and cross bar 53 normally holds the latter and lever 54 in the illustrated position and allows the pen to bear against the sheet *s* under the spring 15 action in arm *r*. The lower end of lever 54 is movable in a radial recess 56 in the described shaft 41 and axially slidable in the latter is a rod 57, one end of which is capable of engaging and moving lever 54 20 against the force of spring 55. The other end of rod 57 projects beyond the rear end of shaft 41 (Fig. 3) and may be engaged and moved by one arm of a bellcrank lever 58, which is pivoted to a bracket on the rear 25 wall of casing A. The other arm of lever 58 is connected by an upwardly extending wire 59 to a unit of the actuating mechanism to be later described. On a lifting of wire 59 pen *p* will be moved away from the 30 sheet *s* and on a subsequent lowering of wire 59, pen *p* will again be allowed to engage the sheet. The movement of pen *p* to and from the record sheet are coördinated with the shifting movement of frame 40 by the 35 actuating mechanism, as will later appear.

It is essential, in certain instances, to wash the hydrometer after each reading. Thus, when the fluid in sample can 20 is sticky size, considerable of this size would 40 adhere to the hydrometer *h* and weight it down, so as to seriously affect the accuracy of the hydrometer readings. Where fluid of this or like nature, is used, I provide means for flushing the hydrometer after 45 each reading has been taken. This periodically cleans the hydrometer and maintains it free from undesired accumulations. By flushing the hydrometer after the reading has been plotted on sheet *s*, the accuracy 50 of the plotted reading is unaffected and the subsequent dilution of the fluid in the sample can by the flushing water causes no difficulty, for the diluted fluid is displaced by fresh undiluted fluid before the next 55 reading is taken.

For flushing the hydrometer *h*, a tank 60 is provided on casing A and supplied with water by an inlet pipe 61 (Fig. 2). Such tank is connected by a pipe 62 to a vane or 60 nozzle 63 which directs the flushing water against the hydrometer as illustrated. The flow of flushing water from tank 60 is controlled by a weighted gravity-operated valve 64, which normally closes the outlet of 65 tank 60. Valve 64 has an upwardly extend-

ing stem 65, which is connected to a lever 66 (Figs. 2 and 5) fixed on a shaft 67 mounted in a bracket on casing A. Also fixed to shaft 67 is a second lever 68, which is connected by a wire 69 to another unit of 70 the actuating mechanism, which periodically opens and closes valve 64 in properly timed relation with the other elements of the apparatus, as will appear.

The actuating mechanism for the various 75 elements heretofore described, includes, as motive power, a clock spring 70 (Fig. 8) and a suitable gear train 71, whereby a shaft 72 may be turned in the direction of the arrow from spring 70. A gear train 73 is 80 provided for connection to a suitable governor in a manner now too well understood in the art to require detailed description or illustration herein. The rotation of the shaft 72 under the action of spring 70 is 85 controlled by an escapement mechanism, which is operated electromagnetically in timed relation with the record sheet *s*. Thus, as diagrammatically shown in Fig. 20, E represents an electric clock, of any 90 suitable type, which is arranged to propel the record sheet *s*. Clock E is electrically connected in series, by wires 74, with a master clock M, a battery 75, and an electromagnet 76. The master clock M causes the 95 record sheet *s* to be moved at a definite time rate. In this instance, the clock E is energized once each minute and thus the 100 record sheet *s* is moved step-by-step by angular movements each of which represents one minute. The electromagnet 76 will obviously be energized once each minute.

The escapement includes an escapement 105 segment 77 mounted to turn on a stud 78 and connected to a gear 79 to turn therewith. In mesh with gear 79 is a rack 80 which is slidably supported in the frame F of the actuating mechanism. The rack 80 110 is slotted, as shown in Fig. 9, to receive an arm 81 pivoted at 82 to frame F. Such arm has an integral and laterally offset extension 83 the upper end of which lies closely adjacent the gear 73' of the gear train 73 described and in the path of pin 84 thereon. A spring 85 tends to move rack 80 to the right, as viewed in Fig. 9, while the clock spring 70 tends to move it to the left, by reason of the pin 84 engaging the arm 83 115 and thus the rack bar. The spring 85 is relatively light and is intended merely to move the gear 79 and segment 77 in a clockwise direction after the pin 84 and arm 83 have been disengaged, as will appear. 120 Therefore, the clock spring 70 will readily overcome spring 85 and will tend to turn segment 77 in a counter clockwise direction. The escapement segment has a series, as ten, 125 radial teeth 86 and between such teeth are 130

laterally projecting teeth 87. A spring arm 88, fixed at one end to frame F, carries a latch 89, also of spring material, which latch normally engages a tooth 86 and prevents movement of shaft 72 under the action of the clock spring 70. Periodically, however, on energization of electromagnet 76, the arm 88 is moved until latch 89 releases tooth 86, whereupon the shaft 72 turns and with it the segment 77. The latter, however, is soon arrested by a projection 90 on arm 88, which projection engages a lateral tooth 87 of the segment and holds it until arm 88 is allowed to spring back into the illustrated position. At such time, tooth 87 will pass freely through a slot 91 in projection 90 and allow the segment 77 to move until the next tooth 86 is arrested by latch 89. It will thus be seen that shaft 72 may be turned by a series, as ten, small intervals, these intervals being so small that the pin 84 does not become disengaged from arm 83. At the end of the tenth interval, however, the end of the segment 77 has been reached and the latch 89 can no longer hold the latter. The release of the segment 77 permits rotation of gear 73' and thus the segment is turned by pin 84 until the latter becomes disengaged from arm 83. As soon as this happens, spring 85, being now unopposed by the clock spring 70, immediately returns the segment 77 into position for a subsequent cycle of operation, the extent of this return movement being limited by the engagement of shoulder 92 on rack 80 with the stop 93. Immediately that pin 84 is free from arm 83, shaft 72 turns through the remainder of the revolution, under speed controlled by a governor, as above mentioned, being eventually arrested by arm 83 which meanwhile has been brought back into proper position by spring 85. Thus, once in each definite time interval, as ten minutes, shaft 72 completes one revolution and, during this interval, makes a series, as ten, very small increments, which do not, except in one instance, as will later be explained, function with the hydrometer apparatus but are suffered since by so doing it is insured that the record sheet s and the actuating units operated by shaft 72 will work in synchronism.

The unit for actuating the hydrometer gripping device will next be described with reference to Fig. 15. This unit consists of a cam 94, fixed on the shaft 72, and a lever 95 pivoted on a cross bar 96 mounted in frame F. Lever 95 is connected intermediate its ends to the rod 39, already described, and at its other end has a roll 96' to ride on the periphery of cam 94 and a knife edge 97 which periodically engages the cam. Cam 94 has dwell portions 98 and 99, a sharp let off portion 100 and a "rise" portion 101. At the start of each cycle, roll 96 engages the dwell portion 98, thereby holding arm 95

lifted and preventing the weighted lever 36 from operating the hydrometer gripping device. At the end of the ten minute interval described, the roll 96 has left dwell 98 and only the knife edge 97 holds lever 95 in raised position. Consequently upon the start of the large step of movement of shaft 72 (which as has been noted is very nearly one revolution) the knife edge 97 will drop sharply off the dwell 98 and drop upon the dwell 99, thereby permitting the lever 36 to operate the hydrometer gripping device. The roller 96 will then traverse the dwell 99 for an interval long enough to permit the plotting of the hydrometer reading and will eventually engage the rise 101, whereby the lever 95 will be raised and the hydrometer released from its clamping device by the consequent raising of lever 36.

The unit of the actuating mechanism for controlling the mechanism for moving the pen p to and from the record sheet s will next be described with particular reference to Fig. 18. Two cams 102 and 103 are fixed to the drive shaft 72. A lever 104, mounted on the cross bar 96, carries on its free end a roll to engage cam 103. Pivoted intermediate its ends to lever 104 at 105 is a lever 106 the free end of which is engageable with the cam 102. Lever 106 is held to its cam 102 by a weight 107 (Figs. 2 and 8) suspended by a wire 108. The rear end of lever 106 is curved on a radius equal to that of the hub 109 of lever 104 and such hub is recessed, as at 110 so that the curved end of lever 106 may lie concentric with hub 109 and to all intents and purposes act as a part thereof. A lever 111, pivoted at one end to a bracket on casing A (Fig. 8) has its free end resting on the curved end of lever 106 and a wire 59 already described, connects the latter to the lever 58. When the lever 111 is lifted above the periphery of hub 109, the pen p is moved away from sheet s, as already described, but when the curved end of lever 106 lies concentric with hub 109, the pen p engages the record sheet. It should be noted that when both levers 104 and 106 are moved equally and simultaneously, no movement of lever 111 takes place and in order to actuate the latter, a relative movement must take place between the levers.

During the several small steps of movement of shaft 72, both levers 104 and 106 are gradually rising equally for the surfaces of both coincide from points 112 to 113. At or about the start of the large step of movement of shaft 72, the points 113 of the cams are engaged by the levers. As soon as this step of movement takes place, lever 105 will be allowed to drop, as cam 102 travels from points 113 to 114 while lever 104 will be maintained in lifted position for some time, viz., until it reaches point 115. Therefore, the lever 111 will be raised shortly after the

shaft 72 commences its large step of movement and thereby the pen *p* will be moved away from sheet *s*. Thereafter, both levers remain stationary but at different levels, so that pen *p* is held away from sheet *s* during the shifting of frame 40. After such shifting of frame 40 has been completed, the lever 104 has reached point 115 and thereafter quickly drops to point 116 and to the same level as lever 106. Thus lever 111 is lowered and pen *p* allowed to engage sheet *s*. Shortly after lever 104 has dropped, as described, lever 106 drops from points 117 and 118 and thereby raises lever 111 and causes pen *p* to be moved away from the sheet *s*. This latter movement of course, occurs before the return movement of frame 40. Thereafter, both levers remain stationary but at different levels to hold pen *p* away from the sheet *s* until the completion of the return movement of frame 40. At such time lever 106 has reached point 119 and is gradually raised from points 119 to 112, thereby allowing pen *p* to be moved into engagement with the record sheet.

The unit of the actuating mechanism for causing the shifting of frame 40 will next be described with particular reference to Fig. 17. Such unit includes a cam 120 fixed on shaft 72 and a lever 121 pivotally mounted on the cross rod 96. Lever 121 is connected to the described wire 45 which holds the shifting lever 44 from movement under the action of gravity. During the many short steps of movement of shaft 72, and for a sufficient time thereafter to permit the pen *p* to be moved away from sheet *s*, as described, lever 121 engages a dwell surface 122 on cam 120. After pen *p* has been disengaged from sheet *s*, lever 121 drops along the surface 123 until it strikes a dwell surface 124, whereby lever 44 is allowed to drop until arrested by the hydrometer *h*, it being understood that the drop of lever 44, permitted by cam 120, is greater than the greatest movement of the lever ordinarily necessary to cause cap 50 to engage the hydrometer. After the frame 40 has been shifted, the lever 121 rides on the dwell surface 124 until the pen *p* is moved into and again moved out of engagement with sheet *s*, whereupon lever 121 encounters the rising surface 125 and gradually lifts the lever 44 until in the illustrated position.

In connection with the shifting of hydrometer *h*, it should be noted that the weight of the lever 44 effective to cause the cap 50 to lower into engagement with hydrometer *h*, may be regulated by means of a counter-weight 126 adjustably mounted on an arm 127 fixed to shaft 141, as shown in Fig. 2.

The unit of the actuating mechanism for operating the flushing water valve 64, will next be described with particular reference to Fig. 14. Such unit includes a cam 128,

fixed to shaft 72 and two levers 129 and 130. Levers 129 and 130 are pivoted together, "scissors like" fashion, at 131 and lever 129 is pivotally supported on rod 96 while lever 130 has a curved end portion 70 adapted to fit into a recess on the hub of lever 129 in a manner analogous to that described in connection with the structure shown in Fig. 18. A lever 132 is pivoted, similarly to lever 111, and has its free end 75 riding on the curved end of lever 131. The described wire 69 is connected to lever 132. A weight 133 is suspended by a wire 134 from lever 130 and functions to lift lever 132 when permitted to do so by the cam. 80 Both levers ride on the periphery of the one cam 128, the lever 130 engaging in advance of lever 129. At the start of the cycle of operations, the cam 128 is positioned as shown in Fig. 14. That is the 85 lever 130 has dropped while lever 129, being slightly in the rear of lever 130, is still in lifted position. Thus, lever 132 is lifted and the flushing water valve 64 is open. At the end of the first 90 small step of movement of cam 128, which occurs substantially one minute after the lever 130 drops, lever 129 is permitted to quickly drop, which by lowering the pivot 131 causes the curved end portion of lever 95 130 to lie in the recess of the hub of lever 129. Thus lever 132 is allowed to drop and thereby close the valve 64. Thereafter, both levers are carried along at equal levels, both being first gradually raised on the portion 100 135, then held raised by the dwell portion 136 until the end of the large step of movement of cam 128, at which time lever 130 drops to lift lever 132 and open valve 64. Thus, the valve is opened at the very end of 105 each cycle of operation and held open until the start of the next cycle.

The various units of the actuating mechanism and in fact all actuating elements of the entire apparatus are characterized in 110 that they are operated by a motor of very small power. That is the clock spring 20 is not sufficiently powerful to produce the sudden movements of the various parts. Consequently, throughout the apparatus, all 115 sharp sudden movements are produced by allowing weighted parts to drop. The relatively large force for the various movements and the relatively large distance through which the various elements must move are 120 thus obtained by gravity. The parts, after having been allowed to drop, can then be raised slowly by the relatively small power exerted by spring 20. For this reason, for example, the peculiar "scissors like" levers 125 are provided, to permit several rapid and relatively powerful movements on each cycle of operation of shaft 72, by means of gravity action. Obviously, many other means may be employed to actuate the va. 130

rious mechanisms described and I do not therefore intend to limit my invention thereto, although the particular actuating mechanism described is important for the 5 reasons pointed out.

A most important feature of the invention consists in the arrangement, whereby a standard hydrometer bulb can be used, due to the provision for intermittent engagement 10 with the hydrometer of parts of the recording apparatus, thus eliminating the necessity for attaching parts to the hydrometer or for special construction of the latter. This arrangement permits the ready substitution 15 of new bulbs, to replace broken ones without the inconvenience and delay necessarily incident to obtaining bulbs of special construction. Moreover, the arrangement permits bulbs with the standard graduations to be used, thus doing away with the necessity for special calibration.

Another feature of importance consists in the utilization of a standard recording thermometer, with the provisions described for 20 making the temperature plotting pen also plot the specific gravity readings. In this connection, it is to be noted that while it is desirable and preferred to provide for plotting both temperature and specific gravity, it is not according to all features of the 25 invention, for the interposition of the thermometric mechanism, as described, has an important function, whether or not the temperature readings are plotted, for it provides for automatic correction of the specific 30 gravity readings.

The invention has been disclosed herein, in an embodiment at present preferred, for 35 illustrative purposes but the scope of the invention is defined by the appended claims rather than by the foregoing description.

What I claim is—

1. In an apparatus of the class described, 40 a container to receive the fluid to be tested, a hydrometer therein, a movable record sheet, a recording stylus to record the hydrometer readings on such sheet, a movable member, a thermometric mechanism interposed between said stylus and member and operative by variations of the temperature of the fluid to move said stylus relatively to said member, and means operable periodically to move said member into engagement with the hydrometer.

55 2. In an apparatus of the class described, a container to receive the fluid to be tested, a hydrometer therein, movable means periodically engageable with the hydrometer and limited in its movement by the height 60 of the hydrometer in the fluid, a thermometric mechanism carried by said means, and an indicator arm carried by said means and movable by said mechanism independently of the movement of said means.

65 3. In an apparatus of the class described,

a container to receive the fluid to be tested, a hydrometer therein, means to periodically grip the hydrometer and hold it in the various positions which it may assume in said container, a movable record sheet, a recording stylus to record the hydrometer readings on such sheet, a movable member, a thermometric mechanism interposed between said stylus and member and operative by variations of the temperature of the fluid to move said stylus relatively to said member, and means operable periodically to move said member into engagement with the gripped hydrometer.

4. In an apparatus of the class described, 80 a container to receive the fluid to be tested, a hydrometer therein, means to periodically hold the hydrometer against movement by the buoyant action of said fluid, a member movable periodically to engage the gripped 85 hydrometer and limited in its movement thereby, a thermometric mechanism carried by said member, and an indicator arm carried by said member and movable by said mechanism independently of the movement 90 of said member.

5. The combination with a recording thermometer, of a member carrying the thermometric mechanism thereof and the stylus arm, a container for fluid whose temperature and specific gravity are to be recorded, means connecting said mechanism to said container so that temperature variations of the fluid may be recorded on the movable record sheet of the thermometer, a 95 hydrometer in said container, means to periodically hold it against movement by the buoyant action of said fluid, means to move said member, and means associated with the latter to engage the held hydrometer and 100 arrest the movement of said member.

6. The combination with a recording thermometer, including the stylus arm, the movable record sheet, and the actuating mechanism for such arm, of a container for 110 fluid, means connecting the latter to said mechanism, a hydrometer in said container, and means to periodically shift said mechanism and its associated arm to a new position on the record sheet, the degree of 115 shifting movement being limited by the height of the hydrometer relative to the fluid in said container.

7. The combination with a recording thermometer, including the stylus arm, the 120 movable record sheet, and the actuating mechanism for such arm, of a container for fluid, means connecting the latter to said mechanism, a hydrometer in said container, means to periodically move said mechanism 125 and its associated arm along the record sheet, the degree of movement of said mechanism being limited by the height of the hydrometer relative to the fluid in said container, and means to move the arm away from the 130

record sheet prior to such movement and toward the record sheet after such movement.

8. The combination with a recording 5 thermometer, including the stylus arm, the movable record sheet, and the actuating mechanism for such arm, of a container for fluid, means connecting the latter to said mechanism, a hydrometer in said container, 10 means to periodically move the said mechanism and its associated mechanism laterally of the record sheet to a position for plotting the hydrometer readings and back again to the position for plotting the tem- 15 perature readings, means associated with the last named means to engage the hydrometer and limit the extent of the first named movement, and mechanism to move the arm toward and away from the record sheet op- 20 erable to move the arm toward the sheet at the end of the movement of the arm in each direction and to move the arm away from the sheet prior to the start of the movement of the arm in each direction.
- 25 9. In an apparatus of the class described, a container to receive the fluid to be tested, a hydrometer therein, means to periodically hold the hydrometer against movement by the buoyant action of said fluid, a member 30 movable periodically to engage the gripped hydrometer and limited in its movement thereby, a thermometric mechanism carried by said member, and an indicator arm movable by said mechanism independently of 35 the movement of said member, said member being subsequently movable away from the hydrometer, and means to move said arm toward the record sheet at the end of the first named movement and away from the 40 sheet prior to the last named movement.
10. In an apparatus of the class described, 45 a container to receive the fluid to be tested, a hydrometer normally free to float therein, an indicator arm, means to periodically move said arm, and a member associated and movable therewith and arranged to engage the hydrometer, whereby the position of the moved arm indicates the relative height of the hydrometer in the fluid in said con- 50 tainer.
11. In an apparatus of the class described, 55 a container to receive the fluid to be tested, a hydrometer normally free to float therein, an indicator arm, means to periodically move said arm, a member associated and movable therewith and arranged to engage the hydrometer, whereby the position of the moved arm indicates the relative height of the hydrometer in the fluid in said container, 60 and means to automatically wash the hydrometer after each engagement of said member therewith.
12. In an apparatus of the class described, 65 a container to receive the fluid to be tested,

a hydrometer normally free to float therein, 65 means to periodically grip the hydrometer and hold it against flotation, a movable indicating arm, a member movable therewith, and adapted to engage the gripped hydrometer as a stop, and means to periodically move said member into and out of engagement with the hydrometer. 70

13. In an apparatus of the class described, 75 a container to receive the fluid to be tested, a hydrometer normally free to float therein, means to periodically grip the hydrometer and hold it against flotation, a movable indicating arm, a member movable therewith and adapted to engage the gripped hydrometer as a stop, means to periodically 80 move said member into and out of engagement with the hydrometer, and means to automatically wash the latter after each engagement of said member therewith.

14. In an apparatus of the class described, 85 a container to receive the fluid to be tested, a hydrometer normally free to float therein, means to periodically grip the hydrometer and hold it against flotation, a movable indicating arm, a member movable therewith, and adapted to engage the gripped hydrometer as a stop, said member being movable by gravity into engagement with the hydrometer, means normally holding said member away from the hydrometer, and 95 means to periodically release the last named means.

15. A recording hydrometer, comprising, 100 a movable record sheet, a recording pen to coöperate therewith, a container for the fluid, a hydrometer normally free to float therein, means to periodically grip the hydrometer and hold it against flotation, a member carrying said pen, means normally holding said member in one position, the 105 member when released being movable by gravity and limited in such movement by the gripped hydrometer, and means movable synchronously with the record sheet to periodically actuate the gripping means and 110 release the holding means.

16. In an apparatus of the class described, 115 a movable record sheet, a recording pen to coöperate therewith, a container for fluid, a hydrometer normally free to float therein, means movable by gravity to grip the hydrometer against movement by flotation, means to hold the gripping means against movement by gravity, a member carrying the pen, means normally holding said member 120 in one position, said member being movable when released by gravity and limited in such movement by the gripped hydrometer, a spring motor, and means driven thereby to suddenly release said gripping means and 125 said holding means at properly timed intervals and to subsequently allow them to return them to their positions.

17. In an apparatus of the class described, a container for fluid, a hydrometer normally free to float therein, means to periodically grip the hydrometer, a member periodically movable into engagement with the latter, a movable record sheet, a pen to coöperate with the latter and movable by said member, means to flush the hydrometer after each operation of the gripping means, said flushing means including a control valve; a cam shaft; cams thereon to control the operation of said gripping means, the movement of said member, and the operation of said control valve; and means to periodically move 40 said shaft through one complete cycle; whereby the hydrometer is gripped, the pen moved, and the control valve opened to flush the hydrometer, one of said cams arranged to hold said valve open at the end of said 45 cycle, and means operable at a predetermined time after the end of said cycle to move such cam sufficiently to release said valve and allow it to close.

18. In an apparatus of the class described, 25 a container for fluid, a hydrometer normally free to float therein, means to periodically grip the hydrometer, a member periodically movable into engagement with the latter, a movable record sheet, a pen to coöperate 50 with the latter and movable by said member, means to flush the hydrometer after each operation of the gripping means, a cam shaft, cams thereon to control the operation of said gripping and flushing means 55 and the movement of said member, and means to periodically move said shaft through one complete cycle; whereby the 60 hydrometer is gripped, the pen moved and

the flushing means operated to flush the hydrometer.

19. In an apparatus of the class described, a container for the fluid to be tested, a hydrometer normally free to float therein, a movable indicator arm, a member associated therewith and adapted to be engaged 45 by the hydrometer on relative movement of the latter and said member toward one another, and means associated with said member to move the hydrometer laterally in the container upon such relative movement into 50 alinement with said member.

20. In an apparatus of the class described, a container for the fluid to be tested, a hydrometer normally free to float therein, a movable indicator arm, and a hollow cone 55 shaped member associated therewith and arranged to receive the upper end of the hydrometer within it and force said end laterally into its apex.

21. In an apparatus of the class described, 60 a container for the fluid to be tested, a hydrometer normally free to float therein, means to periodically hold the hydrometer against flotation, and means movable into engagement with the gripped hydrometer 65 to indicate the relative height of the latter in said fluid.

22. In an apparatus of the class described, a container for the fluid to be tested, a hydrometer normally free to float therein, 70 means to periodically hold the hydrometer against flotation, said holding means when released forming guides to confine the hydrometer within limits against lateral movement in the container.

DANIEL S. HOLT.
